[57] CLAIM

I claim the ornamental design for a vehicle distributor coil cover, as shown and described.

DESCRIPTION

FIG. 1 is a front and upper left perspective view of a vehicle distributor coil cover showing my new design.

FIG. 2 is a front elevation thereof;

FIG. 3 is a top plan view thereof;

FIG. 4 is a left side elevational view thereof, the right side being a mirror image; and

FIG. 5 is a bottom plan view thereof; and,

FIG. 6 is a rear elevation view thereof.
